REAMER.

Application filed November 18, 1923. Serial No. 675,096.

Our invention relates to rotary reamers used in well drilling, and a purpose of our invention is the provision of a reamer having a mandrel upon which a plurality of cutters are removably secured to permit with facility and dispatch the substitution of new cutters when they become worn or broken, and the employment of cutters of different size when it is desired to vary the size of the reamer as a whole.

It is also a purpose of our invention to provide a reamer of the above described character in which the cutters are of annular form and provided with peripheral blades which may be of uniform length to provide a reamer which is concentric or straight with respect to the supporting mandrel, or of graduated lengths to form a reamer which is eccentric or offset with respect to the mandrel.

A further purpose of our invention is the provision of a reamer having means for securely locking the several cutter units against movement on the mandrel; means for attaching the standard overshot to the reamer in the case of a twist off at the drill collar; and cutter units which can be replaced at the rig and without the necessity of the employment of special tools.

Although we have herein shown and will describe only one form of reamer and two forms of cutter units all embodying our invention, it is to be understood that various changes and modifications may be made herein without departing from the spirit of the invention and the spirit and scope of the appended claims.

In the accompanying drawings,

Fig. 1 is a view showing in side elevation and partly in section one form of reamer embodying our invention.

Fig. 2 is an enlarged detailed perspective view of one of the cutter units embodied in the reamer shown in Fig. 1.

Fig. 3 is a view similar to Fig. 2 showing another form of cutter unit embodying our invention.

Referring specifically to the drawings in which similar reference characters refer to similar parts, our invention, in its present embodiment, comprises a tubular mandrel

15 provided at its upper end with a threaded extension 16 which serves to connect a mandrel section thereto, the latter being provided with an annular shoulder 18 and a 55 threaded and tapered connection 19. The extension 19 serves to connect the reamer as a unit to a drill tubing so that the reamer can be rotated in the usual manner, while the collar 18 forms an abutment against 60 which an overshot is adapted to bear in effecting the removal of the reamer from a hole. The lower end of the mandrel 15 is provided with a tapered and threaded extension 20 which is adapted to engage with 65 in the socket end of a section of drill tubing 21.

Mounted upon the mandrel 15 are a plurality of cutter units, each unit, as shown in Fig. 2, comprising an annular body 22 70 provided at intervals upon its periphery with cutter blades 23 having cutting edges 23^a. These cutter units are supported in superimposed relation upon the mandrel 15 by spacing rings 24 which snugly but removably fit upon the mandrel so as to permit the removal thereof as well as the cutter units. The several cutter units and rings are immovably secured upon the mandrel by means of clamping collars 25 and 26, the 75 former threadedly engaging the mandrel directly below the extension 16 so as to permit longitudinal adjustment thereof upon the mandrel in clamping the several rings and the cutter units into tight engagement 80 with each other and against the lower collar 26. The collar 26 abuts against the mandrel and toothedly engages with the adjacent end of drill tubing section 21, as shown at 27, thus retaining the entire cutter assembly 85 from slipping off the mandrel, and, when collar 25 is screwed down snugly, it also holds the cutter assembly against rotation with respect to the mandrel. A lock nut 29 is provided to secure the collar 25 against 90 coming loose during the operation of the reamer.

In Fig. 2 we have shown the cutter units in which the axis of the opening of the annulus 22 intersects the plane of the annulus at an angle other than at right angle which angle, in the present instance, is of 100

substantially 60° . As the blades 23 extend radially from the periphery of the annulus 22, it will be clear that the blades are likewise disposed in a plane corresponding to that of the annulus. However, the cutting edges 23* of the blades are disposed in planes parallel to the axis of the opening of the annulus, as clearly illustrated in Fig. 1 so that the combined effect is to produce 10 a spiral cutting edge when the cutter unit is in applied position upon the mandrel 15.

As clearly shown in Fig. 1, the cutters present side cutting edges having blades or teeth, which cutting edges are inclined to 15 the axis of the mandrel and are semi-helical in appearance. Because of the arrangement of the cutters and because of the fact that the upper end of one cutter is above the lower end of the next above cutter, it will 20 be readily understood that upon rotation of the mandrel each cutter will make a cut which is materially greater in width than the thickness of the cutter.

In Fig. 2 we have shown a cutter unit in 25 which the blades 23 are of graduated lengths so that when in applied position upon the mandrel, as shown in Fig. 1, they produce a cutter, the axis of which is eccentric with respect to the axis of the mandrel. In a cutter of this character an offset cut can be 30 produced, as will be understood.

In Fig. 3 we have shown a cutter unit in 35 which the blades 23 are of uniform length so that when a plurality of such units are 40 in applied position upon the mandrel 15 they produce the effect of a cutter or reamer, the axis of which is concentric to the axis of the mandrel. With such a reamer a straight or concentric cut can be effected.

In practice, the eccentric cutter units 45 mounted upon the mandrel 15 can be removed by first removing the lower clamping coliar 26 so as to permit the substitution of new cutter units, should they become worn or broken, or the application of the concentric cutter units to the mandrel, or cutter units either concentric or eccentric of a greater or less diameter than the other cutter units. It will thus be seen that by the 50 employment of a reamer of this character concentric or eccentric drilling can be effected to form holes of predetermined diameters depending upon the diameter of the cutter units employed.

By virtue of the simple manner in which the reamer may be assembled or disassembled, and the fact that the joints between the reamer and drill tubing are of standard 55 lengths, no special tools are necessary other than the conventional tongs employed for disconnecting the joints of the drill tubing.

What we claim is:

1. A well reamer comprising a mandrel, and a plurality of cutters mounted upon 60 said mandrel through which the mandrel

extends, said cutters having flat top and bottom surfaces which are inclined to the axis of the mandrel and being provided with peripheral teeth.

2. A well reamer comprising a hollow 70 mandrel permitting circulation fluid to be forced therethrough, and a plurality of disc-like cutters mounted upon the mandrel through which the mandrel extends, the planes of the discs being inclined other than 75 at a right angle to the axis of the mandrel.

3. A well reamer comprising a hollow mandrel permitting circulation fluid to be forced therethrough, a plurality of disc-like cutters mounted upon said mandrel through 80 which the mandrel extends, the planes of the discs being inclined to the axis of the mandrel, and spacing rings interposed between said cutters.

4. A well reamer comprising a hollow 85 mandrel permitting circulation fluid to be forced therethrough, a plurality of disc-like cutters mounted upon said mandrel through which the mandrel extends, the planes of the discs being inclined to the axis of the 90 mandrel, spacing rings interposed between said cutters, and means bearing against the top and bottom cutters for preventing their rotation upon the mandrel.

5. A well reamer comprising a hollow 95 mandrel permitting circulation fluid to be forced therethrough, and a plurality of disc-like cutters mounted upon said mandrel through 100 which the mandrel extends, the planes of the discs being inclined to the axis of the mandrel other than at a right angle, said cutters being provided with peripheral teeth.

6. A well reamer comprising a hollow 105 mandrel permitting circulation fluid to be forced therethrough, and a plurality of disc-like cutters mounted upon said mandrel through 110 which the mandrel extends, the planes of the discs being inclined to the axis of the mandrel other than at a right angle, said cutters being provided with peripheral teeth of unequal length.

7. A well reamer comprising a hollow 115 mandrel permitting circulation fluid to be forced therethrough, a plurality of disc-like cutters mounted upon said mandrel through 120 which the mandrel extends, the planes of the discs being inclined to the axis of the mandrel other than at a right angle, said cutters being provided with peripheral teeth, and spacing rings separating said cutters.

8. A well reamer comprising a mandrel, and disc-like cutters having peripheral teeth mounted upon said mandrel, said mandrel extending through the cutters, the planes of 125 the cutters being inclined other than at a right angle to the axis of the mandrel.

9. A cutter for well reamers comprising a disc-like body, a bore through said body, the axis of which is at an angle other than 130

at a right angle to the plane of the body, and teeth formed upon the peripheral surface of the body, said teeth being of unequal length.

In testimony whereof we have signed our ¹⁰ names to this specification.

10. A cutter for well reamers comprising a disc-like body, a bore through said body, the axis of which is at an angle other than at a right angle to the plane of the body, and
